M. J. McNAMARA

RAILWAY GUARD RAIL SUPPLEMENT

Filed June 12, 1923

FIG. 1.

FIG. 2.

FIG. 3.

FIG. 4.

By His Attorney
MATTHEW J. McNAMARA.

C. W. Madsack

UNITED STATES PATENT OFFICE.

MATTHEW J. McNAMARA, OF SCRANTON, PENNSYLVANIA, ASSIGNOR OF ONE-HALF TO JAMES R. FLEMING, OF SCRANTON, PENNSYLVANIA.

RAILWAY-GUARD-RAIL SUPPLEMENT.

Application filed June 12, 1923. Serial No. 644,966.

To all whom it may concern:

Be it known that I, MATTHEW J. McNAMARA, a citizen of the United States, and a resident of Scranton, in the county of 5 Lackawanna and State of Pennsylvania, have invented certain new and useful Improvements in Railway-Guard-Rail Supplements, of which the following is a specification.

10 Among the principal objects which the present invention has in view are: to protect railway frog points from wear; to reduce the maintenance expense incident to the replacement of the usual railway guards 15 used in conjunction with railway frogs or crossings; and to simplify and cheapen the construction.

Drawings.

20 Figure 1 is a plan view of fragments of railway rails constructed and arranged as at a track branch or frog.

Figure 2 is a sectional view on enlarged scale, the section being taken as on the line 25 2-2 in Fig. 1.

Figure 3 is a horizontal section showing the construction and arrangement of the track rail guard and supplement, when constructed and arranged in accordance with 30 the present invention.

Figure 4 is a perspective view of wedges used in conjunction with the guard rail and supplement as disclosed in the present invention.

Description.

As shown in the drawings, the supplement is rigidly attached to guard rails such 40 as indicated by the numeral 9. The supplement consists primarily of a metal wedge plate 10, the upper portion of which is chamfered to form the cam surface 11. The plate 10 is perforated at suitable intervals to receive in service, bolts 12. The bolts 12 are drawn tight by the usual nuts 13 which 45 pass through the web of the guard rail 9 as can be seen best in Fig. 2 of the drawings.

The end bolts 12 are also passed through the end opening slots 14 in wedge blocks 50 15 when the said blocks are used. It will be understood that these blocks are not essential to the operation of the plate 10 though beneficial to the installation thereof. When installed they are disposed as substantially 55 shown in Figs. 2 and 3 of the drawings, be-

ing driven between the web of the guard rail 9 and the plate 10.

Heretofore, the frog points such as indicated in Fig. 1 by the numeral 16 have been protected by the use of guard rails such 60 as indicated by the numeral 9. These rails have been held in service relation to the track rails 17 at the inner side of the track by means of chairs 18 or other suitable devices. Whatever the character of the device 65 they have been secured in service upon the ties 19 in the manner shown in Fig. 1 of the drawings. The frogs 16 usually occur where the tracks are branching or where the track rails are curved. At such points the inner side of the outer rail of the intersecting tracks and the outer side of the guard rail 9 opposite the frog have taken the wear of the flange of their respective wheels.

The frog 16 and construction connected therewith are expensive; therefore when the wear on the frog branch of the tracks begins to endanger the traffic, the guard rail 9 is either moved outward or is replaced. The guard rails according to the present 70 80 construction are of a length to correct any tendency of wheels to leave the tracks when approaching the frog branch. They are also mounted on the ties in a way that to readjust them proves to be a very costly operation.

When using the present invention a relatively short plate 10 is employed just sufficiently long to cover an area parallel with and of slightly greater length than the frog 90 16 and the adjacent sections of the track rails. When the plate 10 is installed in service held by the bolts 12, as shown in Fig. 2 of the drawings, the flange of the carrying wheel of the railway vehicle rides upon and slides down over the inclined surface 11 thereof, shifting the said wheel and the axle with which it is rigidly connected together with the wheel on the other side of the curve. The result of this is that the wheels are 95 placed in position where the flange of the wheel approaching the frog 16 is held away from contact with the point of the said frog.

The plates 10 and the inclined surfaces 11 100 thereof are worn, but as they are worn the wedges 15, if employed in the installation, are driven between the extreme ends of the plates 10 and the web of the guard rail 9 with the result that the plate 10 is moved to- 110

ward the adjacent track rail 17. If the blocks 15 are not used the worn plates 10 can be replaced at a relatively slight expense by plates which are not worn, thus effecting 5 a substantial saving to the road equipped with said wear plates.

While I have herein described the use of the supplement as applied to guard rails without specifying whether the same are 10 new or old, it will be understood that the supplement is used most frequently with guard rails after the same have become worn. It will also be understood that while I have described the wedging members used for 15 shifting the working position of the supplement plate, this is not essential to the functioning of the invention.

Claims.

- 20 1. The combination of a railway frog, a guard rail for said frog disposed in service opposite said frog; and a supplement member therefor removably attached thereto in service transversely alined with said frog 25 and adapted for shifting the wheels of a train in a direction away from said frog, said member having a chamfered surface extending from a thin upper edge juxtaposed in service to said guard rail over 30 which the wheels of a train slide when resting thereon.
2. The combination of a railway frog, a guard rail for said frog disposed in service opposite said frog; a supplement member 35 therefor removably attached thereto in service transversely alined with said frog and adapted for shifting the wheels of a train in a direction away from said frog, said member having a chamfered surface extending 40 from a thin upper edge juxtaposed in service to said guard rail over which the wheels of a train slide when resting thereon; and means for removably securing said member to said guard rail.
- 45 3. The combination of a railway frog, a guard rail for said frog disposed in service opposite said frog; a supplement member therefor removably attached thereto in serv-

ice transversely alined with said frog and 50 adapted for shifting the wheels of a train in a direction away from said frog, said member having a chamfered surface extending from a thin upper edge juxtaposed in service to said guard rail over which the wheels 55 of a train slide when resting thereon; means for removably securing said member to said guard rail; and means for varying the position of said supplement to said guard rail.

4. The combination of a railway frog, a guard rail for said frog disposed in service 60 opposite said frog; a supplement member therefor removably attached thereto in service transversely alined with said frog and adapted for shifting the wheels of a train in a direction away from said frog, said member 65 having a chamfered surface extending from a thin upper edge juxtaposed in service to said guard rail over which the wheels of a train slide when resting thereon; means for removably securing said member to said guard rail; and means for varying the position of said supplement to said guard rail, 70 said means embodying spacing members of variable thickness for inter-position between said supplement member and said guard rail 75 for changing the operating position of said supplement member.

5. The combination of a railway frog; and means in advance thereof for alining the wheels of a railway vehicle therewith, 80 said means embodying an inverted wedge-like member for engaging the flanges of said wheels to cause the said flanges to slide down said wedge-like members to position 85 out of line with the point of said frog.

6. The combination of a railway frog; means in advance thereof for alining the wheels of a railway vehicle therewith, said means embodying an inverted wedge-like member for engaging the flanges of said 90 wheels to cause the said flanges to slide down said wedge-like members to position out of line with the point of said frog; and means for removably securing said wedge-like member in service position.

MATTHEW J. McNAMARA.
